US00D462592S

(12) **United States Design Patent** (10) Patent No.: **US D462,592 S**
Cooper (45) Date of Patent: **** Sep. 10, 2002**

(54) DRILL	DE	9505672	3/1996
(75) Inventor: Vincent P. Cooper , Baltimore, MD (US)	DE	9602972.2	3/1996
(73) Assignee: Black & Decker Inc. , Newark, DE (US)	DE	9507044	7/1996
(73) Assignee: Black & Decker Inc. , Newark, DE (US)	DE	9603012	9/1996
(73) Assignee: Black & Decker Inc. , Newark, DE (US)	DE	9600027	10/1996
(73) Assignee: Black & Decker Inc. , Newark, DE (US)	DE	9602972	12/1996
(73) Assignee: Black & Decker Inc. , Newark, DE (US)	DE	9703272.7	3/1997
(73) Assignee: Black & Decker Inc. , Newark, DE (US)	DE	9604701	4/1997
(73) Assignee: Black & Decker Inc. , Newark, DE (US)	DE	041094	8/1997
(73) Assignee: Black & Decker Inc. , Newark, DE (US)	DE	9703272	9/1997
(73) Assignee: Black & Decker Inc. , Newark, DE (US)	DE	9701649	10/1997
(21) Appl. No.: 29/138,064	DE	9703311	10/1997
(22) Filed: Mar. 6, 2001	DE	9804390.0	5/1998
(51) LOC (7) Cl. 08-01	DE	9804390	1/1999
(52) U.S. Cl. D8/68	DE	49902246	3/1999
(58) Field of Search .... Primary Examiner—Doris V. Coles

Assistant Examiner—T. Chase Nelson

(74) Attorney, Agent, or Firm—Bruce S. Shapiro; Michael P. Leary

(57) **CLAIM**

The ornamental design for a drill, as shown and described.

DESCRIPTION

FIG. 1 is a perspective view of a drill showing my new design.

FIG. 2 is a left side elevational view thereof.

FIG. 3 is a right side elevational view thereof.

FIG. 4 is a front elevational view thereof.

FIG. 5 is a rear elevational view thereof.

FIG. 6 is a top plan view thereof; and,

FIG. 7 is a bottom plan view thereof.

The broken lines shown in FIGS. 1, 4, and 6 are for illustrative purposes only and form no part of the claimed design.
